SUPERHEATER

Filed Aug. 13, 1929

INVENTOR

BY Alfred W. Bruce

S. C. Yeaton

ATTORNEY

UNITED STATES PATENT OFFICE

ALFRED W. BRUCE, OF NEW YORK, N. Y.

SUPERHEATER

Application filed August 13, 1929. Serial No. 385,658.

This invention, more particularly, relates to superheaters for use with locomotive boilers.

It has been the usual practice, in the superheaters heretofore used, to employ steam circulation tube units each having vertical reaches connected to a header and longitudinal reaches extending through the fire tubes of the boiler, the length of the vertical reaches, and of the longitudinal reaches being progressively varied, so as to adapt the circulation tubes to properly accommodate themselves to the superposed fire tubes and the header. This practice is objectionable in that the tube units cannot be made standard in form and size. Another disadvantage of the practice is that the number of return bends which can be employed is limited to the size of the fire tubes.

An object of the present invention is to provide a superheater comprising a header, and a plurality of steam circulation tube units disposed in spaced longitudinal rows and having all of their reaches substantially vertical, thus enabling each of the units to be made of standard form and size, and the number of return bends to be increased as desired, and adapting the superheater for convenient application to an economizer having spaced vertical rows of longitudinal water tubes. Other objects of the invention will hereinafter appear.

The improvement claimed is hereinafter fully set forth.

In the accompanying drawing: The figure is an isometric view of a superheater embodying the invention.

In the practice of the invention, referring descriptively to the specific embodiment thereof which has been selected for exemplification herein, the superheater comprises a horizontally disposed box shaped header 10, embodying the usual saturated and superheated steam compartments. Attached to the

bottom of the header are a plurality of steam circulation tube units 11, each tube unit having one of its ends connected to a saturated steam compartment and its other end connected to a superheated steam compartment. 50 Each tube unit comprises four substantially vertical reaches, 11a, 11b, 11c, and 11d, respectively. At their lower ends, the reaches 11a and 11b, are connected by a return bend, 11e; 55 and the reaches 11c and 11d, by a return bend 11f. The upper ends of the reaches 11a and 11d are connected to the header, and the upper ends of the reaches 11b and 11c are connected by a return bend 11g.

Preferably the tube units are arranged in spaced longitudinal rows, the tube units of one row being staggered with relation to those of adjacent rows.

Particularly novel features of the improved construction are that it enables all of the steam circulation tube units to be made of standard size and form, that each tube unit may be formed with as many reaches and return bends as desired, and that the rows of tube units will fit into the spaces between spaced longitudinal rows of water tubes of an economizer, thus enabling the superheater to be installed or removed as a unit, and insuring the maximum thermal efficiency from 70 the gases of combustion. 75

While one of the preferred forms of construction has been described and shown, it is obvious that many variations in procedure, form, arrangement, and construction may be 80 resorted to, and the invention, therefore, is not limited to the particular embodiment disclosed, but includes such changes and modifications as come within the spirit and scope of the invention as set forth in the appended 85 claims. An instance will be noted with reference to the description of the superheater as being applied to an economizer. It of course will be understood that the device may be similarly used with a low pressure boiler, and 90

that the term is intended to include all types of water heaters broadly viewed, disposed in advance of the combustion chamber of a locomotive.

5 The invention claimed and desired to be secured by Letters Patent, is:

1. A superheater comprising a substantially box-shaped header; a plurality of steam circulation tube units projecting from one side of said header and entering said header through said side, each unit comprising an inlet end and an outlet end, communicating with said header, the units being arranged in spaced rows, the units of each row being spaced and the units of adjacent rows being staggered, the units of alternate rows being aligned, whereby the units of one row will be disposed abreast of the spaces between the units of the adjacent rows, the units of each row being arranged in parallel, one set of alternate tube ends of each row being inlets and the other set of alternate tube ends of said row being outlets; and winding partitions separating said header into compartments whereby all the inlet ends will be in communication and all the outlet ends will be in communication, through different compartments.

2. A superheater comprising a substantially box-shaped header; a plurality of steam circulation tube units projecting from one side of said header and entering said header through said side, each unit comprising an inlet end and an outlet end, communicating with said header, the units being arranged in spaced rows, the units of each row being spaced and the units of adjacent rows being staggered, the units of alternate rows being aligned, whereby the units of one row will be disposed abreast of the spaces between the units of the adjacent rows, the units of each row being arranged in parallel, one set of alternate tube ends of each row being inlets and the other set of alternate tube ends of said row being outlets; and a winding partition providing a pair of compartments in said header whereby all the inlet ends will be in communication through one compartment and all the outlet ends will be in communication through the other compartment.

3. A superheater comprising a substantially box-shaped header; a plurality of steam circulation tube units projecting from one side of said header and entering said header through said side, each unit comprising an inlet end and an outlet end, communicating with said header, the units being arranged in spaced rows, the units of each row being spaced and the units of adjacent rows being staggered, the units of alternate rows being aligned, whereby the units of one row will be disposed abreast of the spaces between the units of the adjacent rows, the units of each row being arranged in parallel, one set of alternate tube ends of each row being inlets

and the other set of alternate tube ends of said row being outlets; and a winding partition providing a pair of compartments in said header whereby all the inlet ends will be in communication through one compartment and all the outlet ends will be in communication through the other compartment, each compartment being comprised of a plurality of spaced communicating sections, the spaces between the sections of one compartment forming the sections of the other compartment.
